UNITED STATES PATENT OFFICE.

GEORGE SANDIFER, OF MOBERLY, MISSOURI.

CAR SEAL.

Application filed December 27, 1920. Serial No. 433,118.

To all whom it may concern:

Be it known that I, GEORGE SANDIFER, a citizen of the United States, and resident of the city of Moberly, county of Randolph, 5 and State of Missouri, have invented certain new and useful Improvements in Car Seals, of which the following is a specification containing a full, clear, and exact description, reference being had to the accompanying drawings, forming a part hereof.

My invention relates to improvements in car seals and has for its principal object the construction of a seal which when applied in use cannot be removed without being destroyed, and consequently prevents its re-use.

In the drawings—

Fig. 1 is a perspective view of my seal 20 in locked position;

Fig. 2 is a longitudinal section of the same;

Fig. 3 is a plan view of the blank out of which the same is made and before it is 25 formed;

Fig. 4 is a perspective view of the hook-engaging spring; and

Fig. 5 is a perspective view of the spring 30 which prevents the disengaging of the fastening or sealing loop.

Referring by numerals to the accompanying drawings:

6 indicates the cut or stamped blank out of which I construct my improved seal. 35 This blank is stamped from a sheet of thin metal, such as tin, and is provided with the portion 7 which forms the bottom of the housing and the portions 8 which form the side walls, the portion 9 which forms the 40 top and the portions 10 and 11 which form the end walls of the housing. The portion 11 is slightly narrower than the portion 10 so that when the blank is bent in final form to form the housing, the slot 12 is provided, 45 through which one end of the sealing loop 13 may be inserted.

In making the seal, the sides 8 are folded at right angles to the bottom 7 thus forming the side walls of the housing 14, the 50 portion 9 is then folded parallel with the portion 7 thus forming the top of the housing, and the portions 10 and 11 are folded at right angles to the portion 8 thus forming the end walls of the housing. When 55 this folding operation has been completed the joints are welded or soldered, as occa-

sion may require, thus forming a housing 14 provided with an entrance opening 12 for the free end of the sealing or fastening loop 13, as illustrated in Fig. 2.

It will be observed from Figs. 2 and 3 that the sealing or fastening loop 13 is formed integral with the material out of which the housing is formed, and its free end is provided with an opening 15 which 65 is adapted to engage with the hook-spring 16, the end 17 of which is welded or soldered to the inside of the bottom of the housing and its free end engaging with the top wall 9 of the housing. (See Fig. 2).

Secured to the opposite end of the housing and to the bottom thereof is a spring 19, the free end of which rests against the spring 16. The spring 19 prevents the free end of the sealing loop 13 from becoming 75 disengaged from the hook 16.

In the operation of my device, after it has been formed substantially as described, the free end of the sealing or fastening loop 13 is inserted through the opening 12 of 80 the housing and is pushed forward on the spring 16 until the end of the spring 16 passes into the opening 15. The end of the loop is then pulled in a reverse direction and past the free end of the spring 19 and 85 when in this position the free end of the loop cannot be detached or unfastened, the spring 16 preventing its withdrawal in one direction and the spring 19 its removal in the opposite direction.

It is obvious that a seal so constructed cannot be removed from use without destroying the seal and thus preventing its re-use. The springs 16 and 19 are secured to the bottom wall of the housing before it is 95 formed and the housing is firmly and securely welded together at its joints and is stamped from a single piece of material, there being no parts to detach and replace.

Having fully described my invention, 100 what I claim is:

A car seal, comprising a rectangular housing stamped from a single sheet of material and provided with an opening in one end, a fastening and sealing loop provided with 105 an opening in its free end and formed integral with the bottom wall of said housing and adapted to be inserted through said opening, a spring secured within one end of said housing adjacent the opening thereof 110 and pointing in a direction away from said opening and having its free end engaging

one of the inner walls of said housing, and a second spring provided with a slightly curved end secured in the opposite end of said housing and pointing in an opposite direction from the first mentioned spring and having its curved free end bearing against the under surface of the first mentioned spring at a point intermediate the ends of the first mentioned spring, said 10 second spring yieldingly holding the free

end of the first mentioned spring against the wall of the housing and acting to force the free end of the first mentioned spring into the eye of the sealing loop, and acting as a stop to prevent the sealing loop from being withdrawn from the first mentioned spring. 15

In testimony whereof, I have signed my name to this specification.

GEORGE SANDIFER.
